UNITED STATES PATENT OFFICE.

HARRY E. CAMPBELL, OF NEW YORK, N. Y.

METAL WINDOW FRAME AND SASHES.

1,189,912.

Specification of Letters Patent. Patented July 4, 1916.

Application filed February 10, 1916. Serial No. 77,364.

To all whom it may concern:

Be it known that I, HARRY E. CAMPBELL, a citizen of the United States, residing at New York, in the county of New York and State of New York, have invented 5 a certain new and useful Improvement in Metal Window Frames and Sashes, of which the following is a specification.

The invention relates to metal window- 10 frames and sashes, and consists in the means more particularly hereinafter set forth, whereby the entrance of dust and air past the joints between sashes and frame is prevented, and whereby the construction is simplified and cheapened.

In the accompanying drawings—Figure 1 is a vertical section of my window-frame and sash on the line 1, 1 of Fig. 6. Fig. 2 is a vertical section on the line 2, 2 of Fig. 6, 20 showing sashes 10, 11 in normal position. Fig. 3 is a partial section similar to Fig. 2, but showing the lower sash 10 raised to the top of the frame, and the upper sash 11 lowered to the bottom of the frame. Fig. 4 is a 25 section on the line 4, 4 of Fig. 2. Fig. 5 is a section on the line 5, 5 of Fig. 3. Fig. 6 is a section on the line 6, 6 of Fig. 1 the sash and members S, T being omitted for the sake of clearness. Fig. 7 is a vertical en- 30 larged section through the sill flange 16 and bar 21.

Similar letters and numbers of reference indicate like parts.

The window-frame comprises a lintel box 35 A, sill B and hollow jambs, generally indicated at C, interposed between lintel and sill, said parts being connected by tie-rods D. The jambs on each side are alike, so that the description of one applies to both. Each 40 jamb is formed of a metal plate E, bent at right angles at its end portions F and G, Fig. 4, the portion F being again bent at right angles to form a flange H. To said flange is secured a plate I by screws Y pass- 45 ing through slots in said plate near one edge thereof; the opposite edge K of plate I is curved inwardly. To the portion G is welded a plate L, having a portion J bent at right angles, the edge M of said portion be- 50 ing curved over to correspond to the curved over edge K of plate I. The parts I and J are in the same plane, and are separated by a space between the curved over edges K and M. By reason of this construction there are 55 formed within the jamb two vertical com-

partments, in which the sash counter-weights 8 and 9 are disposed.

On the inner side of the jamb is bolted the flange of a partition N, separating said weight compartments, to which partition is 60 secured the middle arm of a T-shaped bar O. The outer face of bar O is flush with the outer surfaces of parts I and J; but between the curved over edges K and M and the adjacent edges of bar O narrow vertical slots are 65 left. Through one of these slots passes a plate P, extending laterally from the lower sash 10, and through the other of said slots passes a similar plate Q, extending laterally 70 from the upper sash 11. There are similar plates extending from the opposite sides of said sashes into similar slots in the opposite jamb, so that when said sashes are raised or lowered, said laterally extending plates are 75 guided by said slots. To each laterally extending plate is secured a plate R by bolts passing through slots in said plate R, and each of these extension plates may, therefore, be adjusted on its supporting plate so that the outer edge of the extension plate 80 may be brought into proximity to the inner surface of the portion E of the jamb, Figs. 4 and 5.

Upon one side of the lower half of partition N are bolted a number of leaf springs S, 85 Fig. 2, which at their outer ends carry a vertical angle-strip T, Fig. 2. This strip is disposed below the upper sash 11, and its flange is beveled at its upper end, as shown at U in Fig. 2. When the upper sash is in raised position, the vertical edge of the flange of strip T lies against the curved over edge M of jamb plate J, Figs. 2 and 4. When the upper sash 11 is moved downwardly, it 90 acts upon the beveled upper end U to push the strip T outwardly against the resilience of springs S, so that the sash 11 enters between said strip T and the jamb plate edge M. The strip T is held closely against the side rail of the sash 11 by the springs S, and the joint between said parts is thus kept closed. A similar vertical angle-strip V is carried by 95 leaf springs W bolted to the opposite side of the upper half of partition N. This strip is disposed above the lower sash 10, and its flange is beveled at its lower edge X, as shown in Fig. 2. When the lower sash is in closed position, the vertical edge of the flange of strip V lies against the curved over edge K of jamb plate I, Figs. 2 and 4. When 100 105 110

the lower sash 10 is moved upwardly, it acts upon the beveled lower end X to push the strip V outwardly against the resilience of springs W, so that the sash 10 enters between said strip and the jamb plate edge K. The strip V is held closely against the side rail of the sash 10 by the springs W, and the joint between said parts is thus held closed. When the sashes are in normal closed position, the strips T and V close the portions of the jamb slots not occupied by the projecting plates P, Q of said sashes.

The sashes are suspended by sprocket chains 12 passing over sprocket pulleys 13, the pair of pulleys associated with each sash being mounted on one shaft 14, and the two pulley shafts being journaled in bearings (not shown) in the lintel A.

(as shown) in Figure 11.

The lower rail of the lower sash comprises a plate of sheet metal, formed as shown in Fig. 1, having an inwardly struck up rib 15. When the sash is closed, said rib comes over the upwardly projecting flange 14, Fig. 7, on the sill B. The lower portion 17 of said plate lies against the outer face of flange 16. The rib 15 is secured to a rail plate 18 which extends downwardly over the inner face of said flange 16, and its upper portion 19 is inwardly flanged to be grasped by the operator in raising or lowering the sash. On the sill B is removably secured by screws 20 a slotted bar 21, Fig. 7, between which bar and the sill flange 16 the plate 18 enters.

The hollow jambs each comprise but three plates namely, the plate E, the adjustable plate I and the plate L. The plate E is designed to be formed by a plate-bending machine and to contain the maximum number of bends (three) which such machine is capable of effectively making.

The partition N and the springs S and W are flexible. Consequently when the adjustable plate I is set out to diminish the space between the curved over edges M, K of plate 45 I and plate L, pressure on strip T will be transmitted through springs S, W and partition N to the other strip V, so that the joints between both strips T, V and edges K, M or between said strips and the rails of sashes 50 10, 11 will be tightened simultaneously. When the strip flanges press on said sash rails, these, in turn, are, of course, set outwardly to press on the turned over edges K, M. This arrangement is practically dust and weather-proof.

I claim:

1. A metal window-frame, comprising a hollow member having an elongated guide slot in its inner wall, a sash slidable in said frame and of less length than said member, a plate on said sash entering said slot, and resiliently supported means within said hollow member for closing the portion of said slot not occupied by said plate when said sash is in normal closed position.

2. A metal window-frame, comprising a hollow member having an elongated guide slot in its inner wall, a sash slideable in said frame and of less length than said member, a plate on said sash entering said slot, resiliently supported means within said hollow member for closing the portion of said slot not occupied by said plate when said sash is in normal closed position, and means controlled by said sash for moving said closing means to open said slot when said sash is moved from said normal closed position. 75

3. A metal window-frame, comprising a hollow jamb having a vertical slot in its inner wall, a sash slideable in said frame and of less vertical dimension than said frame, a plate laterally projecting from said sash and extending through said slot into said hollow jamb, and a vertical strip within said jamb, and means for resiliently supporting said strip to bear upon a vertical edge of said slot: the length of said strip being such as to close the portion of said slot which is not occupied by said projecting sash plate when said sash is in normal closed position.

4. A metal window-frame, comprising a hollow jamb having a vertical slot in its inner wall, a sash slideable in said frame and of less vertical dimension than said frame, a plate laterally projecting from said sash and extending through said slot into said hollow jamb, a vertical strip within said jamb and outwardly beveled at one extremity, and means for resiliently supporting said strip to bear upon a vertical edge of said slot: the length of said strip being such as to close the portion of said slot which is not occupied by said projecting sash plate when said sash is in normal closed position, whereby when said sash is slid in a vertical direction to meet the beveled end of said strip, said sash shall move said strip outwardly against the resilience of said strip support and enter between the vertical edge of said strip and the adjacent edge of said slot.

5. A metal window-frame, comprising a hollow jamb having a vertical opening in its inner wall, a fixed vertical partition secured to the inner side of the outer wall of said jamb, a vertical plate on the outer edge of said partition and at right angles thereto and disposed in said opening with a clearance between an edge of said plate and said inner jamb wall, a sash slideable in said frame, a plate laterally projecting from said sash and extending through said clearance into said hollow jamb, a vertical strip within said jamb, means for resiliently supporting said strip on one side of said partition to bear upon a vertical edge of said wall opening: the length of said strip being such as to close the portion of said clearance which is not occupied by said projecting 120 125 130

sash plate when said sash is in normal closed position.

6. A metal window-frame, comprising a hollow member having an elongated opening, a partition within said member and entering said opening to divide the same into two parallel slots, two sashes slideable in said frame and each closing a portion thereof, plates on said sashes respectively entering said slots, and means resiliently supported upon opposite sides of said partition for closing the portions of said slots not occupied by said sash plates when said sashes are in normal closed position.

7. A metal window-frame, comprising a hollow member having an elongated opening, a partition within said member and entering said opening to divide the same into two parallel slots, two sashes slideable in said frame and each closing a portion thereof, plates on said sashes respectively entering said slots, leaf springs secured on opposite sides of said partition, and strips carried by said springs for closing the portions of said slots not occupied by said sash plates when said sashes are in normal closed position.

8. A metal window-frame, comprising a hollow jamb formed of a metal plate bent at right angles upon itself at each end, one of said bent over portions having a flange parallel to the middle portion of said plate, and the other bent over portion being united to an angle-plate having its outer portion disposed in the same plane as said flange, a plate supported on said flange and having

its edge opposite to the edge of said angle-plate, means for adjusting the plate on said flange to vary the width of the vertical interval between said edges, and a slideable sash entering between said edges.

9. A metal window-frame, comprising a hollow jamb formed of a plate bent at right angles upon itself at each end, one of said bent over portions having a flange parallel to the middle portion of said plate, and the other bent over portion being united to an angle-plate having its outer portion disposed in the same plane as said flange, a plate supported on said flange and having its edge opposite to the edge of said angle-plate, means for adjusting said last-named plate on said flange to vary the width of said interval, a fixed partition within said interval dividing the same into two parallel vertical slots, two sashes slideable in said frame, and laterally projecting plates on said sashes respectively entering said slots.

10. A metal window-frame, comprising a hollow jamb having a vertical slot in its inner wall, a sash slideable in said frame, a plate laterally projecting from said sash and passing through said slot, and an extension plate supported on said last-named plate and adjustable to approximate its outer vertical edge to the inner surface of said jamb.

In testimony whereof I have affixed my signature in presence of two witnesses.

HARRY E. CAMPBELL.
